[57] CLAIM

The ornamental design for a pneudraulic installation tool, as shown and described.

DESCRIPTION

FIG. 1 is a perspective view of a pneudraulic installation tool showing my new design thereof from the left side;

FIG. 2 is a right side perspective view thereof;

FIG. 3 is a frontal perspective view thereof;

FIG. 4 is a rear perspective view thereof;

FIG. 5 is a perspective view thereof from above; and,

FIG. 6 is a perspective view thereof from below.

The labels bearing text and or graphics which appear in FIGS. 1–3 and 5, and the stamped or molded text which appear in FIGS. 3, 4 and 6 form no part of the design.
